UNITED STATES PATENT OFFICE

2,056,023

HEAT EXCHANGE APPARATUS

Alexander R. Stevenson, Jr., Schenectady, N. Y.,
assignor to General Electric Company, a corporation of New York

Application December 29, 1934, Serial No. 759,673

11 Claims. (Cl. 62—116)

My invention relates to heat exchange apparatus suitable for use in refrigerating machines.

It is an object of my invention to provide an improved heat exchange device of the type in which heat is transferred between a casing or other body and a fluid medium.

Another object of my invention is to provide an improved arrangement for circulating a fluid medium about a heat exchange device.

10 A further object of my invention is to provide an improved air circulating and frost removing device for refrigerator evaporators.

Further objects and advantages of my invention will become apparent as the following description proceeds, and the features of novelty which characterize my invention will be pointed out with particularity in the claims annexed to and forming a part of this specification.

For a better understanding of my invention reference may be had to the accompanying drawing in which Fig. 1 is a sectional view of a household refrigerator provided with a heat exchange device embodying my invention; Fig. 2 is a sectional view along the line 2—2 of Fig. 1; Fig. 3 is a sectional view along the line 3—3 in Fig. 1, and Fig. 4 is a diagrammatic view of another embodiment of my invention.

Referring now to the drawing, in Figs. 1, 2 and 3 I have shown a refrigerator cabinet having an outer metal wall 10, a compartment 11 to be cooled, an evaporator compartment 12 and a motor and compressor compartment 13. The compartments 11 and 12 are formed by inner metal liners 14 and 15 respectively and are surrounded by thermal insulation 16. The compartment 13 is not thermally insulated and is provided with louvers 17 formed in the outer side walls 10 of the cabinet to admit air to cool the motor and condenser. The refrigerating machine is of the general type shown and described in U. S. Letters Patent No. 1,155,780 granted to Audiffren and Singrin on October 15, 1915. The machine comprises a compression casing 18 and an evaporator 19 secured together on a hollow shaft 20 which is mounted to rotate in bearing brackets 21 and 22 and is driven by a motor 23 through a belt 24. When the compressor and evaporator are rotated by the motor 23 gaseous refrigerant is compressed by a compressor within the casing 18 and is cooled and liquefied by the circulation of air over the casing. The liquid refrigerant passes through a conduit arranged in the hollow shaft 20 to the evaporator 19 where it is vaporized upon the absorption of heat from

the chamber 12, the vaporized refrigerant being returned to the compressor.

From the foregoing it will be apparent that it is necessary to provide an efficient transfer of heat between the evaporator and the compressor casings and the air surrounding them, and also that it is necessary to drive the cooled air from the evaporator compartment 12 into the compartment 11 and to circulate cooling air over the compressor and condenser.

10 In accordance with my invention, I provide a plurality of spaced parallel fins 25 on the evaporator 19 and a plurality of spaced parallel fins 26 on the compressor casing 18, the fins being arranged circumferentially about the evaporator 15 and compressor casing and perpendicular to the axis of rotation. When the evaporator and compressor casings are rotated the fins induce a circulation of the surrounding air. In order to use this circulation of air to provide an efficient 20 transfer of heat between the casings and the surrounding air, and in order to circulate air through the compartments 11 and 13, I provide baffle plates 27 and 28 in the compartments 12 and 13 respectively and secured to the walls thereof. 25 These baffles are comb-like in appearance and have teeth 29 and 30 which fit between the fins 25 and 26 respectively. The teeth 25 and 30 and the baffles 27 and 28 are arranged closely adjacent the evaporator 19 and the casing 18, the 30 space shown between them on the drawing being exaggerated for purposes of illustration. It will be apparent that, as the evaporator 19 and the casing 18 are rotated, the air circulated by such rotation will be diverted or skimmed off by 35 the baffles 27 and 28 and will flow away from the casings and, since the compartments 12 and 13 are each divided by the baffles on one side of the shaft 20, the currents of air produced will circulate across the compartments on the opposite 40 side of the shaft. In order to utilize the circulation of air in the compartment 12 to cool the compartment 11, I provide a semi-cylindrical or arcuate baffle 31, as shown in Fig. 2, extending across the compartment 12, surrounding the upper portion of the evaporator 19 and secured to the liner 15 on a leg 32. I also provide supply and discharge passages 33 and 34, respectively, opening into the compartment 11 on opposite sides of a baffle 35 extending across the compartment and terminating short of the top thereof. Upon reference to Fig. 2, it will be apparent that when the evaporator 19 is rotated in a counter-clockwise direction, as indicated by the arrow 18a, the air will be drawn downwardly from the open- 55

ing 34 into the compartment 12 and will be forced across the compartment by the fins 25 on the evaporator 19, the path of the air being indicated by arrows in the Fig. 2. The air is cooled in circulating from one side of the compartment to the other over the fins 25 and the surface of the evaporator 19 and will then flow upwardly through the opening 33 into the compartment 11, wherein it will circulate up over the baffle 35 and return downwardly on the other side to the passage 34. Frost which may be collected on the evaporator 19 due to the condensation and freezing of moisture thereon will be scraped off by the baffle 27 and will fall to the bottom of the compartment from whence it may be removed. It is readily apparent that the formation of such frost will insure a very small clearance between the baffle 27 and the fins 25 and will thereby provide an efficient circulation of air and a minimum film of air between the baffle and the evaporator. The position of the baffle 27 may be selected to direct the air as desired, and also to remove the frost so that it will be collected where it may be conveniently removed. In the cabinet shown the compartment 12 is provided with a door 36 which may be opened to afford access thereto.

The circulation of air over the compressor casing 18 is accomplished in a manner similar to that employed for the evaporator. When the casing 18 is rotated in a clockwise direction, as shown, air will be drawn through the louvers 17 at the right-hand side of Fig. 3, will be driven through the compartment 13 by operation of the fins 26, and will leave by way of the louvers 17 at the left-hand side of the casing so as to cool the condenser, and also the motor 23. The path of circulation of the air is indicated by arrows.

This arrangement for circulating air minimizes the effect due to the presence of a stagnant insulating film of air closely adjacent the surface of the evaporator and the compressor casings and, for this reason, produces a highly efficient transfer of heat between the casings and the air.

In Fig. 4 I have shown diagrammatically a modification of my invention in which the evaporator is maintained stationary while the baffles or scraping blades are rotated. The refrigerating machine shown comprises a compressor 37 driven by a motor 38 through a belt 39. Gaseous refrigerant is compressed by the compressor 37 and flows to a condenser 40 wherein it is liquefied and flows in predetermined quantities through a valve 41 to an evaporator comprising hollow plates 42 and 43 spaced apart and having smooth inner surfaces. Refrigerant vaporized within the evaporator is returned to the compressor through a suction line 44. In order to provide an efficient circulation of air over the surface of the evaporator, I provide a plurality of baffles or blades 45 driven by a shaft 46 which is an extension of the shaft of the compressor.

These blades are arranged to rotate closely adjacent the smooth surface of the evaporator plates 42 and 43, and as they rotate produce a rapid circulation of air about the evaporators and also prevent the accumulation of any substantial amount of frost thereon. It is evident that if desired other blades may be provided to rotate adjacent the outer surface of the evaporator to further increase the circulation of air and prevent excessive collection of frost. The blades 45 may obviously be driven by a separate motor should it be desired to maintain them in opera-

tion continuously regardless of the operation of the compressor.

From the foregoing it is apparent that I have provided a highly efficient arrangement for transferring heat between the surfaces of a rigid heat exchange body and a fluid medium surrounding that body.

Although I have shown particular embodiments of my invention as applied to refrigerating machines, further modifications will become apparent to those skilled in the art. I do not, therefore, desire my invention to be limited to the particular arrangement shown and described, and I intend in the appended claims to cover all modifications within the spirit and scope of my invention.

What I claim as new and desire to secure by Letters Patent of the United States is:

1. A heat exchange device including a body having a fluid therein, a plurality of parallel fins on said body and arranged circumferentially about the same, and means including a baffle having a portion thereof arranged between said fins for producing a turbulent flow of cooling fluid about said fins, said body and said baffle being relatively rotatable.

2. A heat exchange device including a body having a fluid therein, a plurality of parallel fins on said body and arranged circumferentially about the same, and means including a baffle having portions adjacent the sides of said fins for producing a turbulent flow of cooling fluid about said fins, said body and said baffle being relatively rotatable.

3. A heat exchange device including a body having a fluid therein, a plurality of parallel fins on said body and arranged circumferentially about the same, and means including a baffle having portions adjacent the sides of said fins and adjacent the surface of said body for producing a turbulent flow of cooling fluid about said fins and said body, said body and said baffle being relatively rotatable.

4. A heat exchange device including a body having a fluid therein, a plurality of parallel fins on said body and arranged circumferentially about the same, and means including a comb-like baffle for producing a turbulent flow of cooling fluid about said fins and for removing foreign matter from the fins and the surface of said body, said body and said comb-like baffle being relatively rotatable.

5. An evaporator for refrigerating machines including a body having refrigerant therein, a plurality of parallel fins on said body and arranged circumferentially about the same, and means including a baffle having portions arranged between said fins for producing a turbulent flow of fluid about said evaporator and for removing frost or foreign matter from the surface of said evaporator, said body and said baffle being relatively rotatable.

6. A heat exchange device including a body having a fluid therein, a cabinet providing a compartment surrounding said body, a plurality of parallel fins on said body and arranged circumferentially about the same, and means including a baffle secured to the walls of said compartment and having portions adjacent the sides of said fins and adjacent the surface of said body for producing a turbulent flow of cooling fluid about said fins and said body, said body and said baffle being relatively rotatable.

7. A heat exchange device including a body having a fluid therein, a cabinet providing a com-

partment surrounding said body, a plurality of parallel fins on said body and arranged circumferentially about the same, means including a baffle having portions adjacent the sides of said fins and adjacent the surface of said body for producing a flow of cooling fluid about said fins and said body, said body and said baffle being relatively rotatable, and means including an arcuate baffle secured to the walls of said compartment for directing the circulation of said cooling fluid through said compartment from one side to the other side thereof.

8. A refrigerating machine including a compressor casing and an evaporator arranged for rotation about a common axis, a plurality of parallel fins on said compressor casing and arranged circumferentially about the same, a plurality of parallel fins on said evaporator and arranged circumferentially about the same, and means including baffles having portions arranged between said fins for producing a circulation of air about said casing and about said evaporator.

9. A heat exchange device including a body having a vaporizable refrigerant therein, a cabinet provided with a food storage compartment, a plurality of parallel fins on said body arranged circumferentially about the same, means including a baffle having portions adjacent the sides of said fins and adjacent the surface of said body for providing a turbulent flow of air about said body, said body and said baffle being relatively rotatable, and means utilizing the movement of air caused by the relative movement of said body and said baffle for directing a stream of cooled air through said food storage compartment.

10. A heat exchange device including a body having a vaporizable refrigerant therein, a cabinet provided with a food storage compartment, a baffle extending vertically upward in said food

storage compartment, the upper end of said baffle being spaced from the top wall of said food storage compartment, a plurality of parallel fins on said body and arranged circumferentially about the same, means including a second baffle having portions adjacent the sides of said fins and adjacent the surface of said body for providing a turbulent flow of air about said body, said body and said second baffle being relatively rotatable, and means utilizing the movement of air caused by the relative movement of said body and said second baffle for directing a stream of cooled air through said food storage compartment, said last-mentioned means including an air supply conduit extending from one side of said baffle in said food storage compartment adjacent said body and an air discharge conduit extending from adjacent said body to the opposite side of said baffle in said food storage compartment.

11. A heat exchange device including an evaporator having a vaporizable refrigerant therein, a cabinet provided with a food storage compartment and an evaporator compartment, a plurality of parallel fins on said evaporator and arranged circumferentially about the same, means including a baffle having portions adjacent the sides of said fins and adjacent the surface of said evaporator for providing a turbulent flow of air about said evaporator, said evaporator and said baffle being relatively rotatable, means including an arcuate baffle secured to the walls of said evaporator compartment for directing the circulation of air through said evaporator compartment from one side to the other side thereof, and means utilizing the circulation of air through said evaporator compartment for directing a stream of cooled air through said food storage compartment.
